CIRCUIT INTERRUPTER

Roswell C. Van Sickie, Wilkinsburg, Benjamin P. Baker, Turtle Creek, and Erik H. Hall, Wilkinsburg, Pa., assignors to Westinghouse Electric Corporation, East Pittsburgh, Pa., a corporation of Pennsylvania

Application July 10, 1943, Serial No. 494,212

19 Claims. (Cl. 200—50)

1

This invention relates to circuit interrupters, and, more particularly, to arc extinguishing structures therefor.

A general object of our invention is to provide an improved circuit interrupter in which the over-all space requirements are minimized by employing expandable and contractable or telescopic means relating the arcing contacts with the serially related disconnect contacts.

Another object is to provide an improved pumping arrangement which may readily be employed in conjunction with an interrupter of the foregoing type.

Further objects and advantages will readily become apparent upon a reading of the following specification taken in conjunction with the drawings in which:

Fig. 1 is a vertical sectional view of a circuit interrupter embodying my invention and shown in the closed circuit position;

Fig. 2 is a fragmentary view similar to Fig. 1, but showing the disposition of the movable parts near the end of the opening operation;

Fig. 3 is a view similar to Fig. 2 but showing the disposition of the parts in the fully open circuit position of the interrupter;

Fig. 4 is a fragmentary view in cross-section taken on the line IV—IV of Fig. 1;

Fig. 5 is a fragmentary enlarged vertical sectional view taken on the line V—V of Fig. 1, and shows the disposition of the movable parts at an intermediate point in the closing operation;

Fig. 6 is a fragmentary enlarged vertical sectional view of a modified type disconnect structure, the parts being shown in the closed circuit position;

Fig. 7 is an enlarged fragmentary vertical sectional view of still another modified disconnect arrangement, the parts being shown in the closed circuit position;

Fig. 8 is a fragmentary vertical sectional view taken on the line VIII—VIII of Fig. 7;

Fig. 9 is a vertical sectional view of a modified arrangement for connecting the piston connecting rod with the operating mechanism for the interrupter, the parts being shown in the closed circuit position of the interrupter;

Fig. 10 is a vertical sectional view of a modified type disconnect structure in which during

2

the closing operation the arcing contacts make engagement before the disconnect contacts; and

Fig. 11 is a modified piston connecting arrangement, in which the piston is used entirely for flushing purposes, the parts being shown with the contacts in the fully open circuit position before the arcing pressure has died down.

Referring to the drawings, and more particularly to Fig. 1, the reference numeral 1 designates 10 a suitable base structure which supports at its upper end a support plate 2. Resting on the support plate 2 is a weather-proof casing 3 preferably made of a ceramic material. A support plate 4 rests on the casing 3 and supports a metallic cylinder 5, which is closed at its upper end by a valve cap 6. Disposed internally of the casing 3 is an insulating casing 7 having its ends threadedly secured to a pair of annular brackets 8, the latter being secured, as by bolts 9, to the support plates 2, 4.

The casing 7 is filled with a suitable arc extinguishing fluid 11, in this instance oil, which rises to the level 12 within the interrupter. Disposed within the insulating casing 7 is an arc extinguishing device generally designated by the reference numeral 13. The arc extinguishing device 13 comprises a cylindrical casing 15, which encloses at its lower end a plurality of insulating washers 16, 17 of different internal diameters. Consequently, the insulating washers 16, 17 form a corrugated outer surface for an annular arcing chamber generally designated by the reference numeral 18. Above the washers 16, 17 are a plurality of longitudinally extending segmental or 25 first arcing contacts 19, which are biased radially inwardly by tension springs 20, stop rings 21 limiting the radial inward movement of the stationary first arcing contacts 19. Movable axially within the casing 15 is the movable contact 30 structure for the interrupter generally designated by the reference numeral 22. The movable contact structure 22 comprises an insulating rod 23. An insulating sleeve 24 encloses the insulating rod 23, and a nut 26 maintains a washer 25 against the insulating sleeve 24. Threadedly secured to the lower end of the insulating rod 23 is a movable arcing or first contact member 27. A plurality of insulating rings 29, 30 are disposed about the insulating sleeve 24 between the

movable first arcing contact member 27 and an insulating sleeve 31, the latter being disposed about the insulating sleeve 24. A compression spring 32, disposed between the upper end of the insulating sleeve 31 and the washer 25, serves to maintain the insulating rings 29, 30 in compressed relation. If, through continued use of the interrupter, the insulating rings 29, 30 become warped or otherwise distorted in shape, the compression spring 32 will be additionally compressed; and as a result there will be no severe stress set up to distort the movable contact structure 22.

The outer diameter of the insulating rings 29 are greater than the outer diameter of the insulating rings 30. Consequently, the insulating rings 29, 30 form a corrugated inner surface for the annular arcing chamber 18, the purpose for which will appear more clearly hereinafter.

The movable arcing contact member 27 has an annular arcing surface 33, which cooperates in the closed circuit position, as shown in Fig. 1, with the stationary arcing contacts 19. Passages 34 are formed in the movable arcing contact member 27 and at their upper end terminate adjacent the annular arcing surface 33. An annular valve ring 35 biased downwardly by a compression spring 36, serves to normally close the passages 34 as shown more clearly in Fig. 5. The movable arcing contact member 27, is threaded, as at 37, to threadedly engage a conducting cylindrical member 38, the latter forming a piston chamber generally designated by the reference numeral 39. The lower end of the conducting cylindrical member 38 is bifurcated to provide two integrally formed legs 40 more clearly shown in Fig. 5. A flexible conductor 42 is secured by a screw at one end to one of the legs 40 and at its other end is connected to a terminal stud 43. A piston 44 is slidably operative within the piston chamber 39, and is pivotally connected at 45 to a piston connecting rod 46, the latter having an elongated slot 47 formed at its lower end. A pair of compression springs 48 disposed within the piston chamber 39 serve to bias the piston 44 upwardly. A valve 50 is provided in the piston 44 and serves to control the flow of oil through apertures 51 formed in the piston 44.

A pair of rotatable actuating members 52, pivoted at 53 to a bracket 54, support a pin 55 which extends through the slot 47 in the piston connecting rod 46 as shown more clearly in Fig. 5. A pin 56 is supported at the left-hand end of the actuating members 52 and serves to pivotally connect the actuating members 52 with a pair of operating members 57 intermediate the ends thereof. A pin 58 is supported at the left-hand ends of the operating members 57 and carries a roller 59 which moves horizontally in a roller guide 60 formed by two brackets 61. Pins 63, secured to the right-hand ends of the operating members 57, pass through apertures 62 formed in the legs 40, thus pivotally connecting the piston chamber 39 with the operating members 57 as shown more clearly in Fig. 5.

A link 64 together with a crank arm 65 form a toggle generally designated by the reference numeral 66 which relates rotative movement of the operating shaft 67 to the actuating members 52. A compression spring 69, encircling a spring guide rod 74 and disposed between a spring seat 75 welded to the rod 74 and a fixed bracket 76 through which the spring guide rod 74 slidably passes, serves to bias the knee pin 70 of the tog-

gle 66 in a clockwise direction about the operating shaft 67. An insulating operating rod 71 is pivotally connected at 72 to crank arm 73 fixed to the shaft 67. Consequently, upward or opening movement of the operating rod 71 rotates the operating shaft 67 in a clockwise direction and causes counterclockwise rotative movement of the actuating members 52, this opening movement being assisted by the accelerating spring 69. During the downward or closing movement of the rod 71 the accelerating spring 69 is compressed and the actuating members 52 are rotated in a clockwise direction about the pin 53.

A conducting sleeve 80, slidably passing through the cover 14 of the arc extinguishing device 13, is disposed about the insulating sleeve 31, and has a lost-motion connection therewith. The slots 81 formed in the contact sleeve 80 permit free downward movement of the movable contact structure 22 without tending to compress any oil between the conducting sleeve 80 and the insulating sleeve 31. Disposed at the upper end of the conducting sleeve 80 is a movable disconnect or second contact 82. Energy storing means in this instance comprises a compression spring 83 which encircles the insulating sleeve 31. The spring 83 has its upper end seated on the insulating washer 25 and has its lower end seated on a radially inwardly extending flange portion 85 of the conducting sleeve 80. A stationary disconnect or second contact 87 cooperates with the movable disconnect or second contact 82 and is formed by a plurality of segmental contact members 86 biased radially inwardly by a plurality of tension springs 88. The segmental contact members 86 are secured by screws 94 to an offstanding conducting bracket 89, the latter being supported by a bolt 90 to the support plate 4. A bolt 91, having its lower end threadedly secured to the bracket 89, supports a washer 92 which serves as an upper seat for a compression spring 93, the latter biasing the valve cap 6 to its closed position against the cylinder 5 as shown in Fig. 1. One of the screws 94 also serves to connect one end of a flexible conductor 95 to the conducting bracket 89, the other end of the conductor 95 being electrically connected to the terminal stud 96 extending through the cylinder 5.

It will, therefore, be apparent that in the closed circuit position of the interrupter, as shown in Fig. 1, the electrical circuit therethrough comprises terminal stud 96, flexible conductor 95, screw 94, stationary disconnect or second contact 87, movable disconnect or second contact 82, conducting sleeve 80, longitudinal segmental stationary or first arcing contacts 19, annular arcing surface 33 of movable first arcing contact member 27, conducting cylindrical member 38, leg 40 and flexible conductor 42 to terminal stud 43. When it is desired to break the electrical circuit through the interrupter, or in response to overload conditions existing in the circuit controlled by the interrupter suitable operating means, not shown are actuated to cause upward or opening movement of the insulating operating rod 71. The upward movement of the insulating rod 71 rotates the operating shaft 67 in a clockwise direction being assisted by accelerating spring 69. The clockwise rotation of the operating shaft 67 moves the toggle 66 to cause counterclockwise rotative movement of the actuating members 52 about pin 53. The counterclockwise movement of actuating members 52 causes the operating members 57 to rotate in a clockwise di-

rection about the roller 59, the roller 59 meanwhile moving toward the left, as viewed in Fig. 1 in the roller guide 60.

The clockwise rotative movement of the operating members 51 serves to move the legs 40, and hence the movable contact structure 22, downwardly. This draws an arc 99 between the stationary first arcing contacts 19 and the arcing surface 33 of the movable first arcing contact member 27. The arc is shown more clearly in Fig. 2. During the initial downward movement of the movable contact structure 22 the conducting sleeve 80 remains stationary, and the washer 25 compresses the compression spring 83, frictional engagement between the stationary and movable second disconnect contacts 87, 82 being sufficient to maintain the conducting sleeve 80 in a stationary position. The friction between the conducting sleeve 80 and the upper end of arcing contacts 19 also helps to maintain the sleeve 80 stationary during the initial portion of the opening operation.

Therefore it is apparent that the movable first arcing contact 33 is expanded relative to the movable second disconnect contact 82 as shown in Fig. 2, whereas in the closed circuit position of the interrupter, as shown in Fig. 1, the movable contact 33 and the movable disconnect contact 82 are contracted relative to one another.

The drawing of the arc 99 between the stationary and movable arcing contacts 19, 33 within the annular arcing chamber 18 serves to raise the pressure therein, the arc reacting upon the oil to form gaseous products of decomposition under pressure.

It will be observed that during the initial downward movement of the piston chamber 39 the pin 55 moves up in the slot 47 provided in the piston connecting rod 46 as shown in Fig. 2. Since the oil disposed within the piston chamber 39 is unable, because of the high pressure, to move through the passage 34 and out of the piston chamber 39, the compression springs 48 remain compressed and the pin 55 merely moves upwardly in the slot 47 disposed in the piston connecting rod 46 as shown in Fig. 2.

Continued downward movement of the movable contact structure 22 results in lengthening the arc 99, and further storing energy in the energy storing means. That is, the compression spring 83 associated with the disconnect structure is further compressed. As the arc 99 is lengthened it engages fresh oil disposed in the recesses between the insulating rings 29, 30 and the insulating washers 16, 17. Various aspects of the arc extinguishing device 13 are described and claimed in the United States Patent 2,253,009, which issued August 19, 1941, to Benjamin P. Baker and which was assigned to the assignee of the instant application.

When the movable parts assume the position shown in Fig. 2, the pin 55 is approaching the position where it will strike the top of the slot 47 provided in the piston connecting rod 46 and positively interrelates opening movement of the actuating members 52 with upward movement of the piston 44 relative to the chamber 39. This does three things. First, the upward movement of the piston 44 opens the valve 35 and forces oil within the piston chamber 39 upwardly through the passages 34 and adjacent the arc 99 to facilitate the extinction thereof. Secondly, the upward movement of the piston 44, as positively caused by the pin 55 striking the top of the slot 47, slows down the high speed opening

movement of the operating means for the interrupter. This occurs near the end of the opening stroke and at a time when it is desirable to slow down the high speed opening movement 5 of the operating mechanism. Thirdly, the continued upward movement of the piston 44 following extinction of the arc 99 under the biasing action exerted by the compression springs 48, as permitted by the slot 47, produces a flushing action following arc extinction to flush carbonized products of decomposition upwardly out of the annular arcing chamber 18 through the vent 10.

It will, therefore, be apparent that the initial 15 upward movement of the piston 44 is caused positively by the pin 55 striking the upper end of the slot 47 and that continued upward movement of the piston 44 is permitted by the slot 47. Consequently, the extinction of the arc 99 is not only assisted by the extinguishing action provided in 20 the arc extinguishing device 13, but also by the oil flow out of the piston chamber 39.

The arc 99 may or may not be extinguished 25 at the time in the opening operation indicated in Fig. 2. Heavy current arcs will probably have been extinguished before this point is reached. Light current arcs may not have had sufficient pressure developed to cause their extinction and in this case the flow of oil produced by the piston 30 is of assistance in producing arc extinction.

It will be observed that in the position of the parts shown in Fig. 2 the washer 25 is just engaging the sleeve 84, which is fixed to the sleeve 80, to positively drive the conducting sleeve 80 downwardly. The conducting sleeve 80 is forced positively downward by the washer 25 striking the sleeve 84 at a time when the arc 99 is normally extinguished, and when it is desirable to provide a disconnect gap of sufficient length in the interrupter so that breakdown through the interrupter 35 will not occur as a result of voltage surges passing along the electrical line connected to the interrupter.

Referring to Fig. 3 it will be observed that the 45 washer 25 has served to move the conducting sleeve 80 downward out of frictional engagement with the stationary disconnect contact 87. After the conducting sleeve 80 has been positively disengaged from the stationary disconnect contact 50 87, the force of gravity, and the energy which has been stored up in the energy storing means, in this instance comprising the compression spring 83, serves to drive the conducting sleeve 80 downward to separate the movable disconnect contact 82 from the stationary disconnect contact 87. This provides a disconnect gap of length A as shown in Fig. 3. Fig. 3 shows the disposition of the movable parts in the fully open circuit position of the interrupter, with the movable 55 arcing contact 33 and the movable disconnect contact 82 contracted relative to one another.

It will be observed that in Fig. 3 the piston 44 is disposed at the upper end of the piston chamber 39. Consequently, the upward movement of the 60 piston 44 within the piston chamber 39 not only serves to drive oil out of the passages 34 adjacent the arc 99 to facilitate the extinction thereof, but also the continued upward movement of the piston 44 following extinction of the arc 99 serves to flush decomposed products of decomposition upwardly out of the annular arcing chamber 18 and out through the vent 10.

It will be observed in Fig. 2 that the distance B indicates the amount of expansion between 65 70 75 movable arcing contact 33 and movable disconnect

nect contact 82. Thus, there is a saving of longitudinal space in the interrupter of the distance B. It will, therefore, be apparent that we have provided a novel circuit interrupting structure in which in the fully closed and in the fully open circuit positions the movable arcing contact 33 and the movable disconnect contact 82 are contracted relative to one another, whereas during the initial portion of the opening operation the movable arcing contact 33 and the movable disconnect contact 82 are expanded relative to one another. The valve cap 6, biased downwardly toward the closed position by the compression spring 93, serves to relieve excess pressure created within the interrupter.

To close the electrical circuit through the interrupter the insulating operating rod 71 is moved downwardly by suitable mechanism not shown. The downward movement of the operating rod 71 rotates the operating shaft 67 in a counter-clockwise direction to straighten the toggle 66 and to move the actuating members 52 in a clockwise direction about the pin 53. In the fully open circuit position of the interrupter, as shown in Fig. 3, the pin 63 is below the pin 55. In the fully closed circuit position of the interrupter, as shown in Fig. 1, the pin 63 is above the pin 55. It will, therefore, be apparent that during the closing operation the piston 44 is moved downwardly relative to the piston chamber 39 to draw fresh oil through the opening 100 in the cylinder member 38, through the apertures 51 and into the piston chamber 39 by suction action, the annular valve ring 35 meanwhile remaining closed over the passages 34. The purpose of the annular valve ring 35 is to prevent oil which has been contaminated in the arcing chamber from being drawn into the piston chamber 39 during the closing stroke. This gives the oil circulation which forces fresh clean oil upward through the interrupter and prevents the downward flow of dirty oil.

Fig. 5 shows the disposition of the parts at an intermediate point during the closing stroke with fresh oil being drawn into the piston chamber 39. During the closing operation the pin 55 is constantly maintained at the lower end of the slot 47, not only due to the suction drawn within the piston chamber 39, but also because of the upward biasing action exerted by the compression spring 43. It will, therefore, be apparent that during successive opening and closing operations of the interrupter a unidirectional flow of oil takes place through the piston chamber 39, the oil entering the vent 103 and leaving the piston chamber 39 through the passages 34. The piston 44 is completely charged in the closed circuit position of the interrupter, as shown in Fig. 1, fresh uncontaminated oil now being present within the piston chamber 39 ready to be used during the next opening operation of the interrupter.

It will also be observed that during the closing operation the movable arcing contact 33 engages the stationary arcing contact 19 at substantially the same time that the movable disconnect contact 82 engages the stationary disconnect contact 87. Therefore, we have provided an interrupter in which the disconnect contacts or second contacts remain in engagement while the arcing contacts or first contacts separate to draw an arc 99. Following extinction of the arc 99 the disconnect contacts separate to produce an isolating gap in the interrupter in the fully open circuit position thereof. During the closing operation the arcing contacts engage substantially

simultaneously with the engagement of the disconnect contacts. This reduces the electrical stress on the interrupter produced during the closing operation.

5 This reduced electrical stress is particularly important for high speed reclosing service, during which the contacts must be reclosed before all arc products have been expelled from the interrupter. The simultaneous closing of the serially 10 connected disconnecting break in the uncontaminated oil will thus minimize prestriking and arcing on the reclosing part of the operation and thus assure more favorable conditions in the interrupter for the second opening operation in 15 case the fault still persists.

It will be observed that in the interrupter shown in Figs. 1 through 5 friction is the only force which maintains the disconnect contacts in engagement while the compression spring 83 is being compressed by downward movement of the movable contact structure 22. In certain 20 applications it is desirable to supplement the force of friction holding the disconnect contacts 82, 87 in engagement by positive latching means, 25 and in Figs. 6 through 8 we disclose two such latching arrangements.

Referring more particularly to Fig. 6 it will be observed that we have provided a latching member 105 pivotally mounted at 106 and biased in a clockwise direction about pivot 106 by a compression spring 107. The latch 105 is biased into a latch opening 108 provided in the conducting sleeve 80. Thus should the force of friction tending to maintain the disconnect contacts in engagement decrease through wear of the parts or otherwise, still the provision of the latch 105 would prevent downward movement of the conducting sleeve 80 and movable disconnect contact 82 under the biasing action exerted by the compression spring 83 before interruption of the arc 99. Therefore, downward movement of the movable contact structure 22 causes the washer 25 to compress the compression spring 83, the latch 105 meanwhile positively maintaining the 30 conducting sleeve 80 in its raised position thereby 35 maintaining the disconnect contacts 82, 87 in engagement. However, when the insulating washer 25 strikes the portion 109 of the latch member 105, the latch 105 will be forced in a counterclockwise direction about pin 106 to permit the conducting sleeve 80 to move downward thereby 40 separating the disconnect contacts 82, 87 at a time when the arc 99 is extinguished.

In Figs. 7 and 8 another latching arrangement 55 for the disconnecting structure is shown. Here a latch 113 is disposed within the stationary disconnect contact 87 and is pivotally mounted on a pin 114, a coil spring 115 biasing the latch 113 in a clockwise direction about pin 114 as viewed in 60 Fig. 8. A latch portion 116 of the latch 113 latches under a pin 117 which is fixed to and extends diametrically across the movable disconnect contact 82. A U-shaped latch release wire 119 is secured, as by welding, to a sleeve 118 65 slidable on the sleeve 31 as shown more clearly in Fig. 7. A light compression spring 124 biases the sleeve 118 and the release wire 119 upwardly against an inwardly extending flange portion 125 of the movable disconnect contact 82 as shown 70 in Fig. 7. The latch release wire 119 slidably extends through two apertures 120 formed in washer 25. Consequently, during the initial downward movement of the movable contact structure 22 the latch 113 will maintain the disconnect contacts 82, 87 in engagement, the washer 25 mean-

while moving downwardly to compress the compression spring 83. The washer 25 strikes the sleeve 118 at a time when the arc 99 has been extinguished. When the washer 25 strikes the sleeve 118 and compresses spring 124 under the sleeve 118, the latch release wire 119 will be positively driven downward. The downward movement of the release wire 119 will serve to force the release portion 121 of the latch 113 in a counterclockwise direction about the pin 114 thereby permitting the latch 113 to release the pin 117. Resulting downward movement of the conducting sleeve 80 and separation of the disconnect contacts 82, 87 is caused by the force of gravity and release of the energy stored in the energy storing means 83.

The flange portion 125 of movable disconnect contact 82 will force the release wire 119 and sleeve 118 downward with the conducting sleeve 80 after the pin 117 has been unlatched.

If the interrupter is designed to interrupt currents of such magnitude that the arcing pressure created within the annular arcing chamber 18 is not extremely high, it may be desirable to positively relate upward movement of the piston 44 with opening movement of the operating mechanism during the entire opening stroke. Referring to Fig. 9 it will be observed that the pin 55 is pivotally connected to the piston connecting rod 46 and that in this embodiment of our invention the elongated slot 47 is omitted. By utilizing this construction opening movement of the operating mechanism simultaneously positively causes upward movement of the piston 44 relative to the piston chamber 39 to cause oil to flow upward through the passages 34, past the valve ring 35 and into the annular arcing chamber 18 to facilitate the extinction of the arc 99.

However, the piston construction which we disclose in Figs. 1 through 5 is considered preferable because high speed initial opening movement with no retardation is possible, whereas in the piston arrangement of Fig. 9 the movement of oil out of the piston chamber 39 necessitates the employment of strong accelerating springs to get high speed initial opening movement. For the interruption of low currents with correspondingly low arcing pressures, or in an interrupter of such design that high arcing pressures are not encountered, and where a continued pumping action during the entire opening stroke is desired, the piston construction of Fig. 9 may be used. The charging during the closing operation of the piston chamber 39 in Fig. 9 is identical to that disclosed in connection with the piston arrangement shown in Figs. 1 through 5; consequently, a further description thereof is not deemed necessary for a full understanding of this embodiment of our invention. Since the piston 44 in Fig. 9 is positively related to the operating mechanism, no compression springs 48 within the piston chamber 39 need be used.

In the disconnect construction shown in Fig. 10 provision is made for closing the arcing contacts, or first pair of contacts 33, 19 during the closing operation prior to the closure of the disconnect contacts or second pair of contacts 82, 87. Therefore, if the interrupter is closed during the existence of overload conditions in the circuit controlled by the interrupter, the resulting arc will form at the disconnect contacts 82, 87 and not within the casing 15. Consequently, there is no possibility of contaminating, or lowering the dielectric strength of, the oil within the casing 15 during a closing operation which would be

detrimental during the subsequent opening operation. Instead, the arc would be formed at the disconnect contacts 82, 87 in a region of freely circulating oil which will rapidly recover its dielectric strength. The construction in Fig. 10 utilizes a greater wiping action between the arcing contacts 33, 19 than in the construction shown in Fig. 1. Consequently, the arcing contacts 33, 19 engage before the engagement of the disconnect contacts 82, 87 during a closing operation. The arcing contacts 33, 19 remain in sliding engagement until the movable disconnect contact 82 fully engages the stationary disconnect contact 87, at which time the movable contact structure 22 comes to rest. The opening sequence for the contacts in the embodiment of our invention shown in Fig. 10 is the same as that previously described in Figs. 1-5, that is contacts 19, 33 separate before contacts 82, 87.

20 In the modified piston connecting arrangement of Fig. 11, a longer slot 122 is provided, so that the operating mechanism may move to the fully open circuit position (as shown in Fig. 11) without the pin 55 forceably causing the piston 44 to move. The slot 122 is, consequently, longer than the slot 47. Thus the piston 44 in Fig. 11 remains down until the pressure has subsided in the arcing chamber 18, at which time the piston moves upward solely under the biasing action 25 exerted by the springs 48. The charging of the piston 44 in Fig. 11 during the closing stroke is identical to that previously described. The longer slot 122 permits the piston 44 in Fig. 11 to be operative exclusively as a flushing piston, there 30 being no positive interconnection between the pin 55 and the slot 122 during the opening operation.

It will, therefore, be apparent that we have provided a novel circuit interrupter having a pair 35 of movable contacts which are expandable and contractable relative to one another, the arrangement operating to reduce the longitudinal space occupied by the interrupter. By maintaining both disconnect contacts substantially stationary 40 during the initial portion of the circuit opening operation, the inertia of the moving parts during the initial portion of the circuit opening operation is reduced and a weaker accelerating spring 45 69 may be employed.

It will be observed that we have provided an 50 energy storing means, comprising the compression spring 83, which stores energy during the initial portion of the opening movement of the movable contact structure 22. The release of energy 55 from the energy storing means 83 serves to result in high speed opening movement of the movable disconnect contact 82.

It will be observed that the novel pumping 60 means which we disclose is moved with the movable contact structure 22 and serves to force oil adjacent the movable arcing contact 33 adjacent the arc 99. The piston 44 may be positively interrelated with the opening movement of the operating means as shown in Fig. 9, or the piston 44 65 may have a lost motion connection 47 with the actuating members 52 so that only near the end of the opening stroke is there a positive interconnection between the piston 44 and the actuating members 52. The latter arrangement results in (1) facilitating arc extinction if the arc 70 is not already extinguished at this time, (2) providing a flushing flow of oil following arc interruption, and (3) serving to slow down the high speed opening motion of the movable contact 75 structure 22 near the end of the opening opera-

tion at a time when it is desirable to bring the moving parts to a gradual cushioned stop.

If a longer slot 122 is used the piston 44 will function exclusively as a flushing piston as in Fig. 11. It will be noted that we have provided two alternative latching arrangements to supplement the forces of friction for maintaining the disconnect contacts 82, 87 in engagement during the initial portion of the opening operation.

Although we have disclosed and described specific structures it is to be clearly understood that the same were merely for purposes of illustration, and that changes and modifications may readily be made by those skilled in the art without departing from the spirit and scope of the invention.

We claim as our invention:

1. In a circuit interrupter, a pair of arcing contacts separable to establish an arc, a pair of disconnect contacts electrically connected in series with the arcing contacts, means for separating the disconnect contacts after the arcing contacts have separated to produce an isolating gap in the circuit after the arcing contacts have separated enough for arc extinction, and operating mechanism substantially simultaneously closing both the arcing contacts and the disconnect contacts during the closing operation of the interrupter.

2. In a circuit interrupter, an arc extinguishing chamber, movable contact structure comprising a pair of arcing contacts separable within the arc extinguishing chamber to establish an arc therein and a pair of disconnect contacts electrically connected in series with the arcing contacts and separable outside of the arc extinguishing chamber, means for maintaining the disconnect contacts in engagement during the initial portion of the opening operation of the arcing contacts, means for causing opening movement of the disconnect contacts after separation of the arcing contacts, and means for causing substantially simultaneous closing of the arcing and disconnect contacts.

3. In a circuit interrupter, movable contact structure comprising a pair of arcing contacts separable to establish an arc and a pair of disconnect contacts electrically connected in series with the arcing contacts, means for maintaining the disconnect contacts in engagement during the initial portion of the opening operation, energy storing means in which energy is stored as a result of opening movement of the movable contact structure, and means permitting a release of energy from the energy storing means to separate the pair of serially related disconnect contacts after the arcing contacts have separated enough for arc extinction, and means for causing substantially simultaneous closing of the arcing and disconnect contacts during a closing operation.

4. In a circuit interrupter, a relatively stationary arcing contact cooperable with a movable arcing contact to establish an arc, a relatively stationary disconnect contact, a movable disconnect contact, a lost-motion connection between the movable arcing contact and the movable disconnect contact, means for maintaining the two disconnect contacts in engagement and relatively stationary during the initial portion of the opening operation of the interrupter, means electrically connecting the arcing contacts in series with the disconnect contacts, and means causing opening motion of the movable disconnect contact in a direction toward the movable arcing contact after the initial portion of the opening movement of the movable arcing contact.

5. In a circuit interrupter, a movable arcing contact separable from a relatively stationary arcing contact to establish an arc, a movable disconnect contact separable from a relatively stationary disconnect contact to produce an isolating gap in the circuit after arc extinction, means electrically connecting the arcing contacts in series with the disconnect contacts, expandable and contractable means interconnecting the movable arcing contact and the movable disconnect contact, and means for effecting a closing of the arcing contacts prior to a closing of the disconnect contacts during a closing operation of the interrupter.

6. In a circuit interrupter, a movable arcing contact separable from a stationary arcing contact to establish an arc, a movable disconnect contact separable from a stationary disconnect contact to produce an isolating gap in the circuit after arc extinction, means electrically connecting the arcing contacts in series with the disconnect contacts, telescopic means interconnecting the two movable contacts, and means for effecting a closing of the arcing contacts prior to a closing of the disconnect contacts during a closing operation.

7. In a circuit interrupter, a relatively stationary arcing contact cooperable with a movable arcing contact to establish an arc, a relatively stationary disconnect contact, a movable disconnect contact, means electrically connecting the arcing contacts in series with the disconnect contacts, telescopic means for maintaining the two disconnect contacts in engagement and relatively stationary during the initial portion of the opening operation of the interrupter and meanwhile separating the arcing contacts, and latching means for insuring engagement of the disconnect contacts during the initial portion of the circuit interrupter opening operation.

8. In a circuit interrupter, a pair of spaced apart substantially stationary contacts, a pair of serially related movable contacts each engageable with one of said stationary contacts and completing a series circuit through both pair of contacts, expandable and contractable means interconnecting the pair of movable contacts, the pair of movable contacts being contracted in the closed and in the fully open circuit positions of the interrupter, and means for causing the pair of movable contacts to separate relative to each other to expanded position during the initial portion of the circuit interrupter opening operation while one movable contact separates from its stationary contact and the other movable contact remains in engagement with its stationary contact.

9. In a circuit interrupter, a pair of serially related movable contacts, a pair of relatively stationary contacts, expandable and contractable means interconnecting the pair of movable contacts, means for separating one of the movable contacts from one of the stationary contacts and causing an expansion between the pair of movable contacts, means for subsequently separating the other movable contact from the other stationary contact and causing a contraction between the pair of movable contacts.

10. In a circuit interrupter, a pair of spaced apart substantially stationary contacts, a pair of serially related movable contacts each engageable with one of said stationary contacts and completing a series circuit through both pair of contacts, expandable and contractable means interconnecting the pair of serially related movable

contacts, the pair of movable contacts being contracted in the closed and in the fully open circuit positions of the interrupter, means for causing the pair of movable contacts to separate relative to each other to expanded position during the initial portion of the circuit interrupter opening operation while one movable contact separates from its stationary contact and the other movable contact remains in engagement with its stationary contact, and energy storing means in which energy is stored during the expansion between the pair of movable contacts for moving said movable contacts to their contracted position.

11. In a circuit interrupter, a pair of spaced apart substantially stationary contacts, a pair of movable contacts, one of said movable contacts completing the circuit between said stationary contacts and the other of said movable contacts completing the circuit to one of said stationary contacts, when the interrupter is closed, expandable and contractable means interconnecting the pair of movable contacts, the pair of movable contacts being contracted in the closed and in the fully open circuit positions of the interrupter, the pair of movable contacts being expanded during the initial portion of the circuit interrupter opening operation, and means in which energy is stored during the expansion between the pair of movable contacts and then released to cause a rapid contraction between the pair of movable contacts during the latter portion of the circuit interrupter opening operation.

12. In a circuit interrupter, a pair of serially related movable contacts, expandable and contractable means interconnecting the pair of movable contacts, the pair of movable contacts being contracted in the closed and in the fully open circuit positions of the interrupter, and the pair of movable contacts being expanded during the initial portion of the circuit interrupter opening operation, and latching means operative to insure that there will be an expansion between the pair of movable contacts during the initial portion of the circuit interrupter opening operation.

13. In a circuit interrupter, a pair of serially related movable contacts, expandable and contractable means interconnecting the pair of movable contacts, means moving the pair of movable contacts sequentially and causing an expansion therebetween during the initial portion of the circuit interrupter opening operation, the pair of movable contacts being contracted in the closed in the fully open circuit position of the interrupter, and means moving the pair of movable contacts simultaneously in their contracted positions during the closing operation of the interrupter.

14. In a circuit interrupter, a pair of relatively stationary contacts, a pair of serially related movable contacts, expandable and contractable means interconnecting the pair of serially related movable contacts, means causing the separation of one of the movable contacts from one of the stationary contacts before the separation of the other movable contact from the other stationary contact during the initial portion of the circuit interrupter opening operation to effect thereby an expansion between the pair of movable contacts, the pair of movable contacts being contracted in the fully open circuit position of the interrupter, and means for moving the pair of movable contacts together in their contracted position during the closing operation.

15. In a circuit interrupter, a pair of relatively stationary contacts, a pair of serially related movable contacts, expandable and contractable means interconnecting the pair of serially related movable contacts, means causing the separation of one of the movable contacts from one of the stationary contacts before the separation of the other movable contact from the other stationary contact during the initial portion of the circuit interrupter opening operation to effect thereby an expansion between the pair of movable contacts, the pair of movable contacts being contracted in the fully open circuit position of the interrupter, and means for moving the pair of movable contacts together in their contracted position during the closing operation and substantially simultaneously closing each of the pair of movable contacts with one of the pair of stationary contacts during a closing operation of the interrupter.

16. In a circuit interrupter, a pair of relatively stationary contacts, a pair of serially related movable contacts, expandable and contractable means interconnecting the pair of serially related movable contacts, means causing the separation of one of the movable contacts from one of the stationary contacts before the separation of the other movable contact from the other stationary contact during the initial portion of the circuit interrupter opening operation to effect thereby an expansion between the pair of serially related movable contacts, the pair of movable contacts being contracted in the fully open circuit position of the interrupter, and means for moving the pair of movable contacts together in their contracted position during the closing operation and causing a sequential closing of the pair of serially related movable contacts with the pair of stationary contacts during a closing operation of the interrupter.

17. In a circuit interrupter, first and second relatively stationary contacts, first and second serially related movable contacts, expandable and contractable means interconnecting the first and second movable contacts, means causing the separation of the first movable contact from the first stationary contact before the separation of the second movable contact from the second stationary contact during the initial portion of the circuit interrupter opening operation and causing an expansion between the first and second serially related movable contacts, and means for effecting the movement of both the first and second movable contacts in their contracted position during the closing operation and engaging the first stationary contact with the first movable contact before the engagement of the second stationary contact with the second movable contact.

18. In a circuit interrupter, a rotatable actuating member, an operating member, the actuating member having one end thereof pivotally connected to a position intermediate the ends of the operating member, a piston chamber, one end of the operating member being pivotally connected to the piston chamber, a piston operative within the piston chamber, and the actuating member being pivotally connected to the piston to cause the charging operation thereof.

19. In a circuit interrupter, a rotatable actuating member, an operating member, the actuating member having one end thereof pivotally connected to a position intermediate the ends of the operating member, a piston chamber, one end of the operating member being pivotally connected

to the piston chamber, a piston operative within the piston chamber, and the actuating member being operatively coupled to the piston.
